UNITED STATES PATENT OFFICE

THEODORE S. WILKINSON, OF WASHINGTON, DISTRICT OF COLUMBIA, ASSIGNOR TO
THE GOVERNMENT OF THE UNITED STATES, REPRESENTED BY THE SECRETARY
OF THE NAVY

METHOD AND APPARATUS FOR SMOKE SIGNALING FROM AIRCRAFT

Application filed October 17, 1923. Serial No. 668,968.

(GRANTED UNDER THE ACT OF MARCH 3, 1883, AS AMENDED APRIL 30, 1928; 370 O. G. 757)

This invention relates to improvements in method and apparatus for signaling from aircraft and more particularly for producing smoke signals from airplanes although

5 it is, of course, to be understood that without material modification the apparatus may be used for producing smoke clouds for completely enveloping the airplane or other object in air or on the surface of the earth.

10 It may also be used for lighter-than-air craft, such as dirigibles and balloons.

One of the objects of the present invention is to provide a simple and practical apparatus of the above general character particularly adapted for use in producing smoke signals or smoke screens from aircraft.

20 A further object is to provide an apparatus and the ingredients used therewith having no material effect upon the coverings for the airplane or gas bag according to the craft with which it is used.

25 A further object is to provide an improved method of signaling from air craft by means of "smoke" and it is here to be noted that the term smoke is to be understood as meaning any visible cloud of vaporous material clearly visible at a distance either of actual smoke or a combination of 30 chemicals or elements which when combined produce a clearly visible cloud.

Other objects will be in part obvious and in part hereinafter pointed out.

35 Illustrated in the accompanying drawings are shown two of various possible modifications of the apparatus for practising this invention and in these drawings, Figures 1 and 2, respectively, show diagrammatically two of such types.

40 The apparatus employed may be of any desired type. One satisfactory type is illustrated in Fig. 1 wherein are shown, two cylinders, the numerals 1 and 1' one adapted to be filled with ammonia and the other 45 with a chloride under pressure, having their outlets connected to suitable control valves 2 and 3 actuated from a position convenient to the operator. By opening the valves, the two chemicals are combined and sprayed 50 from the aircraft in such a manner that a

thick dense cloud of vapor or smoke, such as ammonium chloride, clearly visible in the distance, is ejected from the rear of the machine, through the escape pipe. 4.

55 Another form of apparatus shown in Figure 2 may be a tank 1a containing a single smoke-making substance, which may be directly connected through suitable control valves 2a with the exhaust from the engine, 60 thus spraying the ingredients into the exhaust pipe by a nozzle 4a whereby they are heated and ejected to the rear of the machine.

65 In the latter apparatus it is preferable to use from 20% to 60% of oleum combined with chlorosulphonic acid, or a smoke-producing metallic chloride such as stannic chloride or titanium tetrachloride. Any desired type of ejecting nozzle may be used but greater efficiency has been obtained when using a small spray gun for introducing the chemicals directly into the exhaust pipe in the form of a very fine spray, to assist vaporization and smoke-production. This spray 70 nozzle is preferably welded directly into the exhaust manifold and the valve control permits the ingredients to be fed either continuously, thereby to generate a heavy cloud of smoke or, if preferred, the valve may be actuated intermittently to produce the desired dot and dash of smoke according to the 75 Morse or other code.

80 It will thus be seen that a simple and practical apparatus is here devised which 85 may be modified extensively without departing from the scope of the invention according to the particular uses to which the invention is applied.

85 The invention also contemplates a reliable 90 and efficient method of producing smoke signals from aircraft which are clearly visible from long distances or smoke clouds which when used to produce a continuous cloud effect will be of advantage in screening aircraft, vessels, fortifications or troops during 95 maneuvers.

The invention described herein may be manufactured and used by or for the Government of the United States of America 100

for governmental purposes, without the payment of any royalty thereon.

What I claim is:—

1. In combination with an aircraft, a container for oleum and chlorosulphonic acid or the like, means for spraying the smoke-producing chemicals into the exhaust manifold whereby these chemicals are heated by the exhaust gases and ejected in the form of smoke.
- 10 2. In combination with an aircraft, a container for oleum and chlorosulphonic acid, means for spraying the chemicals into the exhaust manifold whereby these chemicals are heated by the exhaust gases and ejected in the form of smoke and means associated with the chemical containers whereby the rate of continuity of flow may be controlled as desired.
- 15 3. In a smoke screen apparatus for aeroplanes propelled by internal combustion engines, means for injecting a spray of liquid composition comprising oleum and chlorosulphonic acid into the exhaust gases of the engines.
- 20 4. In a smoke screen apparatus for aeroplanes propelled by internal combustion engines, means for injecting a spray of liquid comprising chlorosulphonic acid and a predetermined percentage of oleum into the exhaust gases of the engine.
- 25

Signed at Washington, District of Columbia, this 20th day of September, 1923.

T. S. WILKINSON.
